FLYING MACHINE

Russell S. Powell, Takoma Park, Md.

Application November 21, 1933, Serial No. 699,060

10 Claims. (Cl. 244—19)

This invention relates to certain new and useful improvements in flying machines.

An object of the invention is to construct a flying machine in which the customary wings or planes are eliminated and so design the propellers located respectively at opposite sides of the flying machine frame or fuselage as to constitute sustaining means performing the function of a wing or plane and for the forward propulsion of the flying machine.

It is a further object of the invention to provide a flying machine of the foregoing character wherein each propeller is preferably comprised of three individual blades extending in such directions and rotatable on an axis at a peculiar angle relative to the vertical and horizontal axes of the flying machine body so that each blade of the propeller during rotation of the propeller on its axis moves coincidental to a corresponding blade on the other propeller and performs the function of a temporary sustaining element in simulation of a wing or plane, effects ascent of the flying machine and also forward propulsion thereof.

With the above and other objects in view that will become apparent as the nature of the invention is better understood, the same consists in the novel form, combination and arrangement of parts hereinafter more fully described, shown in the accompanying drawings and claimed.

In the drawings:

Figure 1 is a front elevational view of a flying machine constructed in accordance with the present invention, showing a three-bladed propeller at each side of the body or fuselage of the flying machine with corresponding blades of two propellers illustrated in machine sustaining position;

Figure 2 is a top plan view of the flying machine;

Figure 3 is a side elevational view;

Figure 4 is a fragmentary longitudinal sectional view showing a clutch connection between the drive motor and propellers; and

Figure 5 is a fragmentary cross-sectional view and shows the universally connected links forming the drive rod between the motor and propeller.

Referring more in detail to the accompanying drawings, the reference character 10 designates a flying machine comprising a body portion or fuselage 11 with the empennage thereof including an elevator 12, a rudder 13 and a skid wheel 14.

The landing gear depending from the forward end of the fuselage 11 includes rods 15 pivoted

at their inner ends as at 16 to the fuselage 11 with their outer ends diverging and meeting to provide a bearing 17 or the ground wheels 18. Shock absorbing struts 19 extend between the wheel bearings 18 and an appurtenance of the flying machine, being vertically disposed as illustrated in Figures 1 and 3.

Describing the invention from the source of energy to the propellers, the reference character 20 designates a motor suitably supported and housed within the fuselage 11, the drive shaft of the motor 20 being placed into communication with the shaft 21 carrying the worm 22 by means of a manually operable clutch 23 that permits operation of the motor with the propellers at rest.

The devices interposed between the motor 20 and worm 22 for the operation of the propellers 24 that are designated in general by the reference character 24 include the transverse shaft 25 journalled in the side walls of the fuselage 11 by means of bearings 26, the shaft 25 carrying intermediate its ends a worm wheel 27 meshing with the worm 22 for the simultaneous operation of the propellers 24 respectively at opposite sides of the flying machine. A horn or bell-shaped housing 28 is carried by each side of the fuselage 10 and projects outwardly, upwardly and forwardly therefrom, the housing 28 being longitudinally curved with its enlarged flared end anchored as at 29 to the fuselage and enclosing the adjacent projecting end of the transverse shaft 25 as shown in Figure 5. A rod bearing 30 is secured in the outer reduced end of each housing 28 and a second rod bearing 31 is anchored within the housing intermediate its ends.

The bearings 30 and 31 provide support for a sectional rod including sections 32, 33 and 34, the rod section 34 being joined with the adjacent end of the transverse shaft 25 by means of a universal joint 35 adjacent the bearings 26 of the ends of the rod sections 33 and 34 being connected by universal joints 36 adjacent the bearing 31 while the rod sections 32 and 33 are connected by a universal joint 37 adjacent the bearing 30. This particular disposition of the bearings and universal joints eliminates abrupt angles of the sections of the rods and provides for a steady and even rotation of the rod section 32 without vibratory or whipping movement of the several rod sections. The rod section 32 provides a support for a propeller 24.

The formation and disposition of each housing 28 presents the outer end thereof for the support of the rod section 32 in the bearing 30 on a line

offset approximately 62° from the vertical axis of the fuselage and directed forwardly at an angle of approximately 47° as illustrated by dot and dash lines in Figures 1 and 3. Each propeller 24 10 comprises a hub 38 that is fixed to the rod section 32 outwardly of the bearing 30 and carries three pairs of bracket arms 39 set 120° apart and extending in a plane crossing the outer ends of the rod section 32 respectively for the support of a propeller blade 40. Each blade 40 has a minor curve in its direction of travel and is also canted in said direction for accomplishing the purposes ascribed to the several blades of each propeller.

The propellers 24 are simultaneously operated 15 and corresponding blades of each propeller simultaneously move through a cycle of operation. The particular angularity of the rod sections 32 for the support of the propeller causes a pair of corresponding blades to assume the position illustrated in Figure 1 as overlying the fuselage, spread to a substantially flat position and to function as sustaining means for the flying machine in simulation of a wing or plane. The propeller blades travel in the direction of the arrows 40a 20 shown in Figure 2 and when said pair of blades moves from the sustaining position shown in Figure 1, they shift to the forwardly propelling position as illustrated by the downwardly positioned blades in Figure 3, the particular angularity of the rod section 32 and the canting of the blade 40 causing the latter to shift from a substantially flat position as shown in Figure 1 to a broad side position as shown in Figures 2 and 3. During the change of position of the blade from Figures 25 1 to 3, the same travels in a downward direction and effects elevation of the flying machine to supplement the action of the elevator 12. Continued movement of this particular pair of blades through an arc of substantially 180° continues in 30 the forward propulsion of the machine and elevation thereof until the blade moves to a position directly above the fuselage 11 and into sustaining position. As an aid in flight, the usual ailerons 41 are provided and are illustrated as 35 hinged as at 42 to the rear side of each housing 28. The blades 40 of the propeller and housings 28 are formed on stream lines to offer the least resistance to their movement and also for the purpose of aiding in suspension. The presence 40 of coating blades of each propeller above the fuselage in a substantially flat condition performs the function of a sustaining wing or plane and the cycle of movement of the blade effects the forward propulsion of the flying machine and 45 also aids in ascent thereof. It is to be understood that the flying machine may be constructed of any materials desired and it is primarily intended to construct the device for individual use or of a size to carry a pilot and one or more 50 passengers.

From the above detailed description of the invention, it is believed that the construction and operation thereof will at once be apparent and while there is herein shown and described the 55 preferred embodiment of the invention, it is nevertheless to be understood that minor changes may be made therein without departing from the spirit and scope of the invention as claimed.

I claim:—

1. In a flying machine, a fuselage, a propeller at each side of the fuselage adjacent the forward end and each propeller including a series of blades respectively movable in cycles for the suspension, forward propulsion and ascension of the flying machine, stub shafts for the rotatable support 75 of the propellers, each set at an angle of approximately 47° forwardly and 62° outwardly.

port of the propellers, each set at an angle of approximately 47° forwardly and 62° outwardly.

2. In a flying machine, a fuselage, a propeller at each side of the fuselage adjacent the forward end and each propeller including a series of blades respectively movable in cycles for the suspension, forward propulsion and ascension of the flying machine, and corresponding blades of each propeller simultaneously movable through a cycle whereby a pair of blades are positioned over the fuselage in simulation of a plane, a pair functioning as forward propellers and a pair functioning as elevators, stub shafts for the rotatable support of the propellers, each set at an angle of approximately 47° forwardly and 62° outwardly.

3. In a flying machine, a fuselage, a propeller at each side of the fuselage adjacent the forward end and each propeller including a series of blades respectively movable in cycles for the suspension, 80 forward propulsion and ascension of the flying machine, stub shafts for the rotatable support of the propellers, each set at an angle of approximately 47° forwardly and 62° outwardly, and said propeller blades being canted in their direction 90 of rotation.

4. In a flying machine, a fuselage, a propeller at each side of the fuselage adjacent the forward end and each propeller including a series of blades respectively movable in cycles for the suspension, 95 forward propulsion and ascension of the flying machine, stub shafts for the rotatable support of the propellers, each set at an angle of approximately 47° forwardly and 62° outwardly, and said propeller blades being canted in their direction 100 of rotation.

4. In a flying machine, a fuselage, a propeller at each side of the fuselage adjacent the forward end and each propeller including a series of blades respectively movable in cycles for the suspension, 105 forward propulsion and ascension of the flying machine, and corresponding blades of each propeller simultaneously movable through a cycle whereby a pair of blades are positioned over the fuselage in simulation of a plane, a pair functioning as forward propellers and a pair functioning as elevators, stub shafts for the rotatable support of the propellers, each set at an angle of approximately 47° forwardly and 62° outwardly, and said propeller blades being canted in their direction 110 of rotation.

5. In a flying machine, a fuselage, a propeller at each side of the fuselage adjacent the forward end and each propeller including a series of blades respectively movable in cycles for the suspension, 120 forward propulsion and ascension of the flying machine, stub shafts for the rotatable support of the propellers, each set at an angle of approximately 47° forwardly and 62° outwardly, and said propeller blades being canted in their direction 125 of rotation, and curved in their direction of rotation.

6. In a flying machine, a fuselage, a propeller at each side of the fuselage adjacent the forward end and each propeller including a series of blades respectively movable in cycles for the suspension, 130 forward propulsion and ascension of the flying machine, and corresponding blades of each propeller simultaneously movable through a cycle whereby a pair of blades are positioned over the fuselage in simulation of a plane, a pair functioning as forward propellers and a pair functioning as elevators, stub shafts for the rotatable support of the propellers, each set at an angle of approximately 47° forwardly and 62° outwardly, and said 140 propeller blades being canted in their direction of rotation, and curved in their direction of rotation.

7. In a flying machine, a fuselage, a propeller at each side of the fuselage adjacent the forward end and each propeller including a series of blades respectively movable in cycles for the suspension, forward propulsion and ascension of the flying machine, a source of energy for the operation of the propellers and a clutch element 145 interposed between the source of energy and propeller 150 of the propellers.

pellers, and means forming communication between the source of energy and propellers including a sectional shaft, a housing carried by the fuselage for each sectional shaft, bearings for the shaft and universal connections between the sections of the shaft, said housings being of substantially horn shape, curved in the direction of its longitudinal axis and outwardly, forwardly and upwardly directed.

10 8. In a flying machine, a fuselage, a propeller at each side of the fuselage adjacent the forward end and each propeller including a series of blades respectively movable in cycles for the suspension, forward propulsion and ascension of the flying machine, and corresponding blades of each propeller simultaneously movable through a cycle whereby a pair of blades are positioned over the fuselage in simulation of a plane, a pair functioning as forward propellers and a pair functioning as elevators, a source of energy for the operation of the propellers and a clutch element interposed between the source of energy and propellers, and means forming communication between the source of energy and propellers including a sectional shaft, a housing carried by the fuselage for each sectional shaft, and an aileron hinged to the rear edge of each housing.

15 9. In a flying machine, a fuselage, a propeller at each side of the fuselage adjacent the forward end and each propeller including a series of blades respectively movable in cycles for the suspension, forward propulsion and ascension of the flying machine, and corresponding blades of each propeller simultaneously movable through a cycle whereby a pair of blades are positioned over the fuselage in simulation of a plane, a pair functioning as forward propellers and a pair functioning as elevators, a source of energy for the operation of the propellers and a clutch element interposed between the source of energy and propellers, and means forming communication between the source of energy and propellers including a sectional shaft, a housing carried by the fuselage for each sectional shaft, and an aileron hinged to the rear edge of each housing.

20 10. In a flying machine, a fuselage, a propeller at each side of the fuselage adjacent the forward end and each propeller including a series of blades respectively movable in cycles for the suspension, forward propulsion and ascension of the flying machine, and corresponding blades of each propeller simultaneously movable through a cycle whereby a pair of blades are positioned over the fuselage in simulation of a plane, a pair functioning as forward propellers and a pair functioning as elevators, a source of energy for the operation of the propellers and a clutch element interposed between the source of energy and propellers, and means forming communication between the source of energy and propellers including a sectional shaft, a housing carried by the fuselage for each sectional shaft, and an aileron hinged to the rear edge of each housing.

25 30

at each side of the fuselage adjacent the forward end and each propeller including a series of blades respectively movable in cycles for the suspension, forward propulsion and ascension of the flying machine, a source of energy for the operation of the propellers and a clutch element interposed between the source of energy and propellers, and means forming communication between the source of energy and propellers including a sectional shaft, a housing carried by the fuselage for each sectional shaft, and an aileron hinged to the rear edge of each housing.
